J. KAUFMAN

CONTAINER

Filed Dec. 17, 1924

UNITED STATES PATENT OFFICE.

JOSEPH KAUFMAN, OF NEW YORK, N. Y., ASSIGNOR TO AMERICAN SAFETY RAZOR CORPORATION, OF NEW YORK, N. Y., A CORPORATION OF VIRGINIA.

CONTAINER.

Application filed December 17, 1924. Serial No. 756,471.

My present invention relates generally to containers and to their association and co-ordinately to such an association of containers as will on the one hand suggest and drive 5 home effectively the advertising and selling features of the article contained in one of them, and as will on the other hand give to the user of the article a physical evidence of the benefits resulting from its use.

10 As is well known, the development of self-shaving is more or less tied up with the development of what is known as the safety razor, of which there are numerous types on the market.

15 While the factors of convenience and cleanliness have had a great deal to do with the almost universal practice of men to shave themselves, the greatest factor that has resulted in its universal development is

20 the saving resulting, particularly in view of the fact that the cost of shaving in establishments known as barber shops, has increased with the general rise in the cost of all commodities and of service.

25 In order to bring home this factor of saving and consequently to increase the use of safety razors and their sale, slogans such as "Shave and save" have been adopted to bring out in as pithy and as attractive a 30 way as possible the fact that by shaving oneself with an outfit, the initial cost of which is relatively small and the upkeep of which is also correspondingly small, a relatively large saving can be effected.

35 It is obvious that slogans such as "Shave and save" have been presented to the individual hitherto by advertisements of various characters, which, however, do not generally bring home the effect thereof at the 40 time desired, namely, just at the time when the user is actually shaving.

One of the objects of my invention is to form a razor case container of such a character that the slogan "Shave and save" or 45 its import, will be forcibly presented to the user of a razor contained in such case every time the individual uses such razor.

The human mind is limited, however, more or less to the specific, and in calculating savings, the average person keeps in

mind only the fact that a single shave costs, let us say, twenty cents at a barber shop, and that a similar operation at home, pro-rated for a sufficiently long time, taking into consideration the initial cost and the cost of replacement and upkeep, may be, say only two cents, thus giving a saving of eighteen cents. The average individual, however, does not sit down to calculate, and even after he has done so, does not keep in mind 55 that while at each shave he saves eighteen cents, that in the aggregate, for a period of a year, the saving will run over and above \$60.00 and even where he does realize and keep in mind this aggregate of saving, 60 there is no actual evidence thereof as by a distinct segregated accumulation of such saving over a period of time.

Another important object of my invention is the provision of such a character of case 70 for the safety razor, which will not only at all times remind a man of the fact that he is saving by shaving himself and will suggest to him the fact that he permit the savings to accumulate, but which will give him 75 a physical arrangement whereby accumulations of such savings can be made so that at the end of any stated period, as for instance, at the end of six months or a year, he can not only tell definitely what the total so saving has been as against the total cost, but in addition he will have such saving in a segregated fund.

My invention further provides an association with a razor, of a money container, so 85 that when a person opens the shaving container to run over the razor for a shaving operation there will be right at hand not only a remainder of the economy to be effected, but there will also be presented to the user a coin slot leading to a container in which the money so saved at that particular shave can be put away and kept segregated.

Another important object of my invention is the provision of a new, useful, simple, 95 economically constructed and effective container, and more particularly one intended to associate containers having a single aim in view, one of which is to serve as a bank.

For the attainment of these objects and 100

of such other objects as may hereinafter appear or be pointed out, I have illustrated one embodiment of my invention in the drawings wherein—

5 Fig. 1 is a perspective view of the container with one end open, exposing the shaving outfit;

10 Fig. 2 is a perspective view of the container with the opposite end open;

15 Fig. 3 is a vertical cross-section through the container; and

Fig. 4 is a view similar to Fig. 1 with the contents removed and parts broken away so as to show the detailed construction.

20 Fig. 5 is a view of a detail showing the manner of joining the ends of the body blank.

25 Upon comparing Figs. 1 and 2 of the drawing, it will be observed that my container comprises generally the body portion 10 which is open at opposite ends and is divided intermediate such open ends by the partition 11 into upper and lower compartments 12 and 13, for which compartments the members 14 and 15 serve as closures.

30 The body member 10 is preferably formed of a single blank of sheet material bent so as to form the front wall 16, the rear wall 17 and the side walls 18 and 19, the ends of the blank being joined at 20' as shown more clearly in Fig. 5 of the drawing by having each end bent back upon itself and received between the doubled-up portions of the other end. The body member is finished off exteriorly by an outer covering 23 which may be of a material to imitate leather and which as shown is arranged to cover the exterior or all four walls and to be passed over the upper and lower ends of the walls and down 40 upon the upper and lower inner portions thereof.

45 The partition 20 preferably made of metal is arranged to be secured within the body member 10 and intermediate the upper and lower ends thereof, this partition 20 being preferably of such dimensions as to be received snugly within said body 10 and is cut out as shown in 21 so as to provide for the overlapping joint or connection 20'. This 50 partition 20 may be secured in position in any preferred or desired manner as by glue.

55 In the upper compartment 12 is positioned the composite structure comprising the base member 26 and the block 27, shaped as shown in Figs. 1 and 3 of the drawing and arranged so as to form seats and compartments for a razor and a blade receptacle as shown in Fig. 1 of the drawing.

60 The block 27 is provided with the slot 30 passing therethrough and in order that the inclusion of this slot may not reduce the available area of the container 25, it is placed relatively close to one wall, preferably close to the front wall of the body member 10 and the base member 26 is cut away in

registry with the slot as shown in Fig. 3 of the drawing. Partition 20 is similarly cut away. In this manner I provide a slot 30 of a size to receive coins of various values. This slot is open at one end to the upper receptacle in which, as stated, are to be received the shaving implements, and is open at its other end through the partition 20 into the lower compartment 13.

70 The cover members 14 and 15, the former for the upper compartment 12 and the latter for the lower compartment 13 are of any desired or preferred character, contours, and dimensions and each is pivoted to the body member 10 as by the hinge members 40 and 41 secured together by pintle 42.

75 Upon viewing Fig. 4 of the drawing, it will be observed that I use the leaf spring 44 which is of such a character that it maintains the covers in either the closed or open position. The cover members 14 and 15 which may preferably be alike in all respects, each comprises the stamping 45 having the continuous side walls as shown and provided with the flange 46 cut away centrally at 47 and also cut away at predetermined points as shown at 48, through which openings 48 are received the prongs 49 cut out from the closure base member 50 and bent around the flange 46.

80 The side members 45 and the cover base member 50 are finished off exteriorly in any desired or preferred manner as by being covered by a material 51, in imitation of leather.

85 Attached to the front of the wall 17 of the container 12, is the member 53 (see Figs. 2 and 3) provided with an opening 54 in which is to be received catch 55, movable within the casing 56 and controlled to be moved to its locked and unlocked position by means of a conventional type of key. The compartment 12 is, as already stated, intended to contain a safety razor outfit as shown in Fig. 1 of the drawing, whereas the compartment 13 is intended to serve as a savings bank and for this reason, as has already been described the compartment 13 is arranged to be locked, whereas the compartment 12 is arranged to be opened at will and not locked.

90 It will be understood from the description thus far given, that I have provided a safety razor container, which is so constructed that anyone attempting to use the razor contained therein for shaving, will not only necessarily have brought to his attention the fact that there is a saving resulting from shaving himself, but also that such a saving should be deposited into the compartment 13 through the opening 30. In addition to this, the closures for this container are so constructed that while the closure for the razor compartment can be 95 opened and closed conveniently and without

difficulty, the closure for the savings bank can be opened only by the operation of a key.

Having now described my invention and 5 illustrated its use, what I claim as new and desire to secure by Letters Patent is:

1. A closure for a container having an open-ended body portion, said closure including a stamping having continuous side 10 walls and a flange, portions of which are cut away to provide openings, and a closure base member having portions struck up therefrom, said struck up portions being in the form of tabs which are passed through the 15 openings and bent down upon the adjacent material.

2. In a device of the character described, a container having a body portion open at

its opposite ends, closures for said open ends, a partition associated with the body portion and intermediate the open ends thereof whereby superimposed compartments are formed, a saddle block in one of the compartments to receive parts of the shaving apparatus and a coin slot through 25 the saddle block leading to the other compartment and means for locking the coin compartment, said closures including a stamping having continuous side walls and a flange, predetermined portions of which 30 are cut away, and a closure base member having struck up portions adapted to engage the flange at the cut away portions thereof.

In witness whereof, I have hereunto signed my name this 8th day of Dec., 1924.

JOSEPH KAUFMAN.
